DETACHABLE SOAP TRAY FOR SCRUB BUCKETS AND THE LIKE

Filed April 8, 1929

Inventor:
Ethel H. Williamson
By A. G. Fletcher, atty.

UNITED STATES PATENT OFFICE

ETHEL H. WILLIAMSON, OF ST. LOUIS, MISSOURI

DETACHABLE SOAP TRAY FOR SCRUB BUCKETS AND THE LIKE

Application filed April 8, 1929. Serial No. 353,288.

This invention relates to certain new and useful improvements in a soap tray and has for its primary object the purpose of providing the tray with means whereby it can be 5 quickly attached or detached to or from the rim of a bucket.

Another object of the invention is in providing the detachable soap tray with means for securing it to the rim of a bucket in a manner wherein the liquid contained in the tray 10 can drain into the bucket.

A further object of the invention is in providing the tray with a series of depending 15 prongs for cooperable engagement with the side wall of a bucket for securing the tray to the bucket.

Other and further objects will appear in the specification and be specifically pointed 20 out in the appended claims, reference being had to the accompanying drawings, exemplifying the invention, and in which:—

Figure 1 is a prospective view showing this improved detachable soap tray secured 25 to a bucket.

Figure 2 is an enlarged fragmentary vertical section taken approximately on the line II—II of Fig. 1.

Figure 3 is a sectional view of a part of the device taken on the line III—III of 30 Fig. 2.

Referring by numerals to the accompanying drawings 1 designates a metallic bucket having the usual carrying bail 2, said bucket having the usual beaded rim 3 and adapted to 35 be mounted on the rim 3 in this improved soap tray 4.

The soap tray 4 is provided with a bottom wall 5 having a curved front edge 6 which conforms approximately to the curvature of 40 the rim 3 of the bucket and extending upwardly from the bottom wall 5 is a wall 7 which extends around the side and rear edges of the bottom wall and around the opposite ends of the edge 6 as designated at 8.

Extending from the front edge 6 of the bottom wall 5 are a pair of spaced depending legs 9 and disposed between the legs 9 is a relatively long depending leg 10, said leg 10 also being extended from the front edge 59 of the bottom wall 5.

In the manufacture of a soap tray of this character and from the disclosure of the drawings, the legs 9 and 10 are formed integral with the bottom wall 5 although if desired the legs 9 and 10 can be made separate and secured in a well known manner to the underside of the bottom wall 5 and depended therefrom but in the instance of this disclosure, during the formation of the leg 10 the material immediately adjacent the front edge 6 of the bottom wall 5 is buckled upwardly and downwardly as designated at 11 and bent under and rearwardly of the wall 5 as designated at 12 and is then bent forwardly and downwardly as shown in Fig. 2, 65 the leg 10 being disposed rearwardly of the legs 9.

In mounting this improved soap tray to a bucket which will serve as a holder for cleaning elements such as bar soap and a sponge, the legs 9 and 10 are engaged overlappingly of the side wall 13 of the bucket 1 in which the legs 9 will be disposed against the inner periphery of the wall 13 while the leg 10 will engage the outer periphery of the wall and as the legs 9 and 10 are made somewhat resilient there is a tendency for said legs to cling against the wall 13 of the bucket thereby securely holding the tray in position on the rim 3 of the bucket.

The vertical portion 11 of the leg 10 and the forward portions 8 of the upwardly inclining wall 7 of the tray 4 will provide abutments for preventing the cleaning elements supported in the tray from falling therefrom into the bucket.

Any liquid content forming in the tray will drain forwardly into the bucket by traversing the legs 9 and the depending apron portions 14 formed between a respective leg 9 and the leg 10. The flowing of the liquid or water content from the tray being augmented by the groove 15 which is formed in each of the legs 9. The groove 15 of each leg 9 and the groove 16 formed in the leg 10 provide a construction for stiffening the legs.

When the soap tray is secured in position as described on the bucket, the bucket can be moved from place to place and the soap tray 4 will be carried thereby and for de-

taching the tray from the bucket a mere pulling apart movement with respect to the bucket and the tray is effected in which the legs 9 and 10 will be withdrawn from clinging engagement with the wall of the bucket.

What I claim is:

1. A soap tray having a bottom wall, and a series of integrally formed prongs depending therefrom, said prongs providing means for cooperably engaging the tray to the side wall of a bucket, one of said prongs being intermediately disposed and adapted to engage the outside of the bucket and having an upwardly projecting part.
2. A detachable soap tray for a bucket comprising a bottom wall having a circular side edge for conformity with the rim of the bucket, a pair of longitudinally grooved depending prongs for cooperation with the inside of the side wall of the bucket extended from the bottom wall of the tray adjacent the circular side edge thereof, said bottom wall having its circular edge portion projecting over the rim of the bucket, and a centrally disposed prong for engagement with the outside of the bucket having an upwardly extending part.
3. A tray for a bucket comprising sheet material having a pair of spaced integrally formed depending prongs, a third integral prong depended from the tray between said pair of prongs being out of bucket engaging alignment therewith, and an apron portion formed on the tray between said prongs.

ETHEL H. WILLIAMSON.
